UNITED STATES PATENT OFFICE

2,510,147

SIDE VENTING ROCKET

Leslie A. Skinner, Berkeley, Calif.

Application March 7, 1945, Serial No. 581,537

3 Claims. (Cl. 102—49)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to an improved construction of rocket and more particularly to an improved nozzle means for venting the propelling gases from the rocket motor chamber.

A serious problem involved in rocket design, especially those employing fast propellants, resides in providing a large propelling charge in conjunction with sufficient free area for the flow of the propelling gases without producing an excessive differential pressure between the head end and the nozzle end of the motor chamber.

It is therefore a primary object of this invention to provide a construction of motor chamber having an improved venting means for the propelling gases in the form of ports or vents formed in the annular wall of the motor chamber to permit the radial flow of the gases therethrough and into expanding nozzle means from which the gases are discharged rearwardly of the rocket.

Still another aim of the invention is to provide such an improved nozzle construction which can additionally function as stabilizing means in lieu of or as an adjunct to the conventional tail fin assembly.

Other objects and advantages of the invention will hereinafter become more fully apparent from the following description of the drawing, which illustrates preferred embodiments thereof, and wherein:

Figure 1 is a longitudinal, substantially central sectional view, partly in elevation, of a rocket constructed in accordance with the invention;

Figure 2 is a cross sectional view of the rocket taken substantially along a plane as indicated by the line 2—2 of Figure 1; and

Figure 3 is an end view in elevation looking toward the rear end of a slightly modified form of the invention.

Referring more particularly to the drawing, wherein like reference characters designate like or corresponding parts throughout the several views, 5 designates generally a rocket constructed in accordance with the invention and including a head or bursting chamber 6 containing a charge of high explosive 7 located in the cavity thereof. The rear end of the head 6 is reduced and threaded to form a nipple 8 to receive the internally threaded forward end 9 of a motor chamber 10. Motor chamber 10 is provided with an integral venturi 11 at its rear end which, if desired, may be normally closed by a conventional safety valve 55

2

such as a blow out disk, not shown. A propelling charge, designated generally 12 is contained in the motor chamber 10 and includes a plurality of powder sticks or grains 13 supported by a powder trap 14. Powder trap 14 includes a rod 15 which extends centrally through the grains 13 and which is provided with a threaded end which engages a threaded recess 16 in the nipple 8. The opposite end of the rod 15 is provided with a head 17 for retaining the powder sticks 13 on the rod 15. The individual powder sticks 13 are spaced from one another and from the nipple 8 and the head 17 by spacing disks 18. As seen in Figure 1, the diameter of the powder sticks 13 is somewhat less than the interior diameter of the cylindrical motor chamber 10 so that the periphery of the powder sticks are spaced from the annular wall of the motor chamber.

The parts previously described may be of any conventional construction and form no essential part of the present invention. The invention includes a plurality of openings or ports 19, formed in the cylindrical wall of the motor chamber 10 and which, as seen in Figures 1 and 2, are arranged in longitudinal rows. A plurality of circumferential spaced hollow lobes 20 are formed integral with or suitably connected to the exterior of the motor chamber 10 and are disposed lengthwise thereon. The lobes 20 are closed at their forward ends, as seen at 21, and are provided with open rear ends 22. The outer portions of the lobes 20 are disposed in rearwardly diverging relationship to the cylindrical wall of the motor chamber 10 and are of substantially the same thickness throughout their lengths, so that the volume of each of the lobes 20 is progressively increased from its closed forward end 21 to its open rear end 22. As clearly indicated in Figure 2, the motor chamber 10 is provided with the same number of rows of openings 19 as lobes 20 and the openings of each of the rows are disposed to open into a lobe.

From the foregoing, it will be obvious that when the powder sticks 13 are ignited, which may be accomplished in any conventional manner, not shown, the propelling gases created thereby, instead of being entirely released through the venturi 11, will be also released through the openings 19 and the lobes 20. The nozzle means formed 50 by the openings 19 and the lobes 20 will accommodate the release of the majority of the propelling gases so that as a result thereof a much larger quantity and a faster burning propellant may be utilized with the improved rocket 5 than is capable of use with rockets previously known.

The gases discharged from the motor chamber 10 by means of the openings 19 and lobes 20 will pass radially outward through the openings 19 and impinge against the rearwardly diverging outer portions of the lobes 20 which will thus act as baffles for deflecting the propelling gases rearwardly and through the open discharge ends 22 of the lobes. The lobes 20, in addition to functioning as a part of the improved venting nozzles, will also function as stabilizing fins for stabilizing the rocket while in flight in lieu of or as an adjunct to a conventional fin assembly, not shown.

In Figure 3 a slightly modified form of the invention is disclosed wherein the lobes 20 are replaced by a substantially conical nozzle element 23 which is secured around the motor chamber 10, adjacent its forward end and which diverges rearwardly, relatively to the cylindrical wall of the motor chamber, and which is open at its rear end. The length of the conical nozzle element 23 is substantially the same as the length of each of the lobes 20 and the nozzle element 23 is disposed in substantially the same relative position on the motor chamber 10 as the lobes 20. In the embodiment of the invention shown in Figure 3, the openings 19, not shown, may be arranged in rows, as in Figures 1 and 2, or, if desired and preferably, may be disposed entirely around the cylindrical wall of the motor chamber 10.

The rocket shown in Figure 3 will function substantially in the same manner as previously described in the description of the rocket shown in Figures 1 and 2. The propelling gases in the motor chamber will be discharged radially outward into the chamber, formed by the cylindrical wall of the motor chamber 10 and the conical wall of the nozzle element 23, and said gases will impinge against the rearwardly diverging conical wall and be deflected thereby rearwardly and 40

toward the open rear end of the nozzle element 23.

Various modifications and changes are contemplated and may obviously be resorted to, without departing from the spirit and scope of the invention as hereinafter defined by the appended claims.

I claim:

1. In a rocket, a motor chamber provided with a plurality of radially disposed ports for venting the propelling gases of the motor chamber, and a plurality of hollow lobes mounted on the exterior of the rocket and into which the ports open, said lobes being disposed lengthwise of the rocket and being closed at their forward ends and open at their rear ends.

2. A rocket as in claim 1, and said lobes being flared from their forward to their rear ends.

3. A rocket as in claim 1, and said lobes having their outermost portions disposed in rearwardly diverging relationship relatively to the contiguous portion of the motor chamber to provide baffle surfaces to deflect the propelling gases, impinging thereon, rearwardly, and to gradually increase the volume of the lobes toward their 25 open ends.

LESLIE A. SKINNER.
